UNITED STATES PATENT OFFICE.

GEORGE S. STRONG, OF PHILADELPHIA, PENNSYLVANIA, ASSIGNOR TO
JOHN T. MORRIS, TRUSTEE, OF SAME PLACE.

VALVE-GEAR.

SPECIFICATION forming part of Letters Patent No. 315,972, dated April 14, 1885.

Application filed June 16, 1884. (No model.)

To all whom it may concern:

Be it known that I, GEORGE S. STRONG, a citizen of the United States, residing in Philadelphia, Pennsylvania, have invented certain 5 Improvements in Valve-Gear for Steam-Engines, of which the following is a specification.

My invention consists of mechanism, described and claimed hereinafter, by which the valve of a steam-engine may be operated from 10 the crank-shaft or axle and connecting-rod, the movement obtained being essentially the same as that obtained by devices which form the subjects of my applications for Patents No. 118,216, filed January 21, 1884, allowed 15 April 11, 1884, and No. 118,025, filed January 19, 1884, allowed May 31, 1884.

In the accompanying drawings, Figure 1, Sheet 1, is a side view of my improved valve-gear applied to a locomotive-engine; Fig. 2, a 20 plan view; Fig. 3, a modification of part of Fig. 1; and Fig. 4, Sheet 2, a view representing a modification of my invention.

Referring to Figs. 1 and 2, A is a connecting-rod of the engine; P, the axle of the driving-wheel P', and Q the crank-pin to which the end of the rod A is adapted. To this pin is secured a return-crank, R, one end of a rod, S, being connected to the pin of this crank, and the other end, by a pin, c, to a link, K, 30 which is connected by a pin, x, to the rod A.

The lower end of a lever, H, is connected to the link K, the upper end of the lever being connected by the fulcrum-pin d to one end of a rod, F, the opposite end of which is connected to a block, E, adapted to a segment, D, 35 permanently secured to any part of the frame of the engine, the block being adjustable on the segment and being connected by any suitable system of rods and levers to the stopping, starting, and reversing lever of the engine.

The short arm b' of the lever H is connected by a pin, d', to a rod, G, which is hinged to the valve-rod B.

Referring to the application for a patent 45 filed by me January 21, 1884, Serial No. 118,216, it will be seen that part of the above-described valve-motion is substantially the same as that shown in Figs. 8 and 9, Sheet 3, of the said application, and referred to but not claimed 50 in the specification, the result of the motion on

the valve, which may be an ordinary slide-valve, being also the same, the pin d' traversing in a course indicated by the diagram, Fig. 6, Sheet 4, of the said application, and by the diagram, Fig. 7, in the drawings connected with 55 the application for a patent filed by me January 19, 1884, Serial No. 118,025. The only difference between the valve-motion shown in Fig. 1 and that shown in Fig. 3 is that in the latter the rod S is connected to the link K by the same pin, 60 b, which connects the said link to the lever H, whereas in Fig. 1 the lever is connected to the link at a point between the pins c and x, the result in both cases being the same if the throw of the pin of the return-crank be properly proportioned, the throw in Fig. 1 being indicated by the dotted circle w, and the radius of this circle being equal to the distance between the dotted line t t, representing the center line of the lever H when the piston is at half-stroke, 70 and the pin c when the piston is at the end of its stroke, the same rule being observed in the modification, Fig. 4, where the radius of the dotted circle w', representing the throw of the pin of the return-crank, is equal to the distance 75 between the said line t t and the pin b.

In cases where no cut-off is required the valve-rod B may be connected directly to the pin d of the lever H, as shown in Fig. 3, and as also shown in my said application No. 80 118,025, filed January 19, 1884, and allowed May 31, 1884.

The fixed segment D is an important element of the combination claimed hereinafter, as it effectually resists the backlash due to 85 the reciprocation of the valve.

It should be understood that I do not claim, broadly, the operating of a valve from the connecting-rod A and the pin of a return-crank on the crank-pin of an engine. The fixed segment, lever H, rods G and F, and valve-rod B, 90 being shown in my aforesaid applications for patents, are also hereby disclaimed; but

I claim as my invention—
1. The combination, in a valve-gear for 95 steam-engines, of the following elements, namely: first, the fixed segment D, and the block adjustable thereon; second, the lever H, the connecting-rod A, link K, rod S, and return-crank R on the crank-pin of the crank- 100

shaft or axle; and, third, the rod F, connecting the said adjustable block to the pin *d* of the lever H, to which lever is also connected the valve-rod, all substantially as set forth.

5 2. Valve-gear for steam-engines, in which the following elements are combined, namely: first, the fixed segment D, and a block, E, adjustable thereon; second, the lever H, having its fulcrum-pin connected to the said block, 10 and having an arm, *b'*, connected to the valve-spindle; and, third, the connecting-rod A,

link K, and rod S, and the return-crank R on the crank-pin of the shaft or axle, all substantially as set forth.

In testimony whereof I have signed my name 5 to this specification in the presence of two subscribing witnesses.

GEORGE S. STRONG.
